UNITED STATES PATENT OFFICE.

GARDNER B. GRAY, OF PITTSBURGH, PENNSYLVANIA, ASSIGNEE, BY MESNE ASSIGNMENTS, TO AUTOMATIC TRAIN CONTROL & SIGNAL COMPANY, OF PITTSBURGH, PENNSYLVANIA, A CORPORATION OF DELAWARE.

ELECTRIC SWITCH.

1,115,810.

Specification of Letters Patent.

Patented Nov. 3, 1914.

Application filed August 30, 1909. Serial No. 515,259.

To all whom it may concern:

Be it known that I, GARDNER B. GRAY, a citizen of the United States, residing at Pittsburgh, in the county of Allegheny and State of Pennsylvania, have invented a new and useful Electric Switch, of which the following is a specification.

This invention has reference to improvements in electric switches and is designed to 10 provide an electric switch of general application but which at the same time is particularly useful in connection with an automatic safety signal system for railways for which system Letters Patent No. 909083 were granted to me on January 5, 1909.

The present invention is designed to provide an electric switch capable of rapid movement in one direction with a sluggish return, or to move sluggishly on the application 20 of the switch actuating means and, when released, to return quickly to the initial position, the structure being such that the switch may be set to act in either manner with facility.

In accordance with the present invention there is provided a switching means responsive to variations in pressure, increasing pressure of a fluid causing the active movement of the switch and decreasing pressure 30 of the fluid causing the return movement of the switch.

The fluid pressure may be generated in any suitable manner, but since it is customary on railway trains to have a constant 35 source of fluid pressure in the air-brake system, such fluid pressure may be utilized for the operation of the switch by suitable controlling means such as shown in the aforesaid Letters Patent or by any other suitable 40 controlling means.

Within the switch structure there may be lodged a sufficient quantity of a liquid, preferably one which is not materially affected by low temperatures, and this liquid may be 45 acted upon by air pressure from the brake system so that through the intermediary of a suitable pressure responsive device such for instance as a Bourdon tube, an electric circuit, or electric circuits may be controlled 50 either automatically or at the will of an

operator depending upon the character and purpose of the circuit.

The invention will be best understood from a consideration of the following detailed description taken in connection with the accompanying drawings forming a part of this specification in which drawings,

Figure 1 is a longitudinal section, with parts in elevation, of an electric switch structure embodying the present invention. Fig. 2 is a section of the line A—B of Fig. 1. Fig. 3 is a section of the line C—D of Fig. 1. Fig. 4 is an end elevation of the structure of Fig. 1 from the switch end, with parts omitted. Fig. 5 is a section of the line E—F of Fig. 4. Fig. 6 is a section of the line G—H of Fig. 1.

Referring to the drawings there is shown a body structure 1, which is shown more or less diagrammatically, that is, the structure illustrated may be changed as may be found necessary for varying conditions, or for the purposes of manufacture.

At one of the ends of the body structure 1, there are formed two chambers 2—3 which may be closed at one end by a cap plate 4. The chamber 2 is entered by a pipe 5 coming from any suitable source of compressed fluid, such, for instance as the pressure side of an air-brake system on a train, especially when the device forming the subject matter of the present invention is installed on a railway train.

Lodged in the chamber 3 is a piston 6 normally urged toward that end of the chamber 3 remote from the cap plate 4 by a spring 7 housed in the chamber 3. The spring 7 engages at one end the piston 6 and at the other end is engaged by a block 8 in turn controlled by a set screw 9 passing through a threaded hole in the cover 4 and this set screw may be secured in any adjusted position by a lock nut 10. The chamber 2 at the bottom, that is the end remote from the cap plate 4, communicates with the corresponding end of the chamber 3 through a conduit 11 formed in the body portion 1, and where the conduit 11 opens into the chamber 3 it is formed into a valve seat for the reception of a valve 12, this valve hav-

ing through it a small passage 13, for a purpose which will presently appear. The valve 12 is held against undue movement with relation to its seat by means of a suitable cage 14, which may be screwed to a nipple 15 formed on the end wall of the chamber 3 where the valve is located.

Leading off from the end of the chamber 3 carrying the valve 12 is a conduit 16 leading to a small valve chamber 17 near the other end of the body 1 from that occupied by the chambers 2 and 3. Access to the chambers 17 is had through an opening normally closed by a screw plug 18. The valve chamber 17 is formed with a seat for valve 19, and from this valve seat there leads another conduit 20 in a direction toward chamber 3 and ultimately terminating in a small chamber 21 entered by a screw plug 22 having a longitudinal passage therethrough for a purpose which will presently appear. Adjacent to the chamber 21 is another chamber 23 to which access may be had through a passage normally closed by a screw plug 24 and in this chamber there is formed a seat for a valve 25 from which valve seat there leads a passage or conduit 26 opening into the chamber 3 at a distance above the conduit 16, that is, the opening of the conduit 26 into the chamber is closer to the cap plate 4 than is the opening of the conduit 16 into the same chamber.

Carried by the screw plug 22 and communicating with the passage there-through is a Bourdon tube 27 which may be of flattened contour as best indicated in Fig. 5 and at the free end of this tube there is secured a clip 28 which may be separated from the tube 27 so far as any electric connection therewith is concerned by a layer 29 of insulating material. The clip 28 carries on the side corresponding to the outer surface of the tube 27 a conducting plate 30, which, as will hereinafter appear, is designed to operate as a bridging conductor.

Secured to the end of the body portion 1 remote from the chambers 2 and 3 is a plate or block 31 of insulating material made fast to the body by suitable screws 32. The block 30 or plate 31 carries a suitable number of binding posts 33 each acting as a clamp screw for an electrical terminal finger 34 or 35 as the case may be. The fingers 34-35 are carried on opposite sides of the block 31 and are in the path of the bridging plate or block 30 in one extreme or other of its travel under the action of the Bourdon tube 27. The two fingers 34 may constitute the terminals of a suitable electric circuit and the two fingers 35 may constitute the terminals of another electric circuit.

Let it be assumed that the chamber 2 has within it a quantity of some liquid, preferably a mobile liquid which will not freeze under temperatures to which the device is

liable to be subjected, there being numerous oils which will answer the purpose, and let it further be assumed that the normal level of the liquid is below the pipe 5. If now air under pressure be introduced into the chamber 2 through the pipe 5 the pressure of the air on the surface of the liquid within the chamber will force the liquid through the conduit 11 and by the valve 12 into the chamber 3 and will there act on the piston 6 to move the same against the action of the spring 7. The liquid under pressure passing to the chamber 3 will find ready access thereto because of the opening of the valve 12 and the piston 6 will yield to the pressure against the action of the spring 7, the degree of pressure necessary to move the piston being regulated by the tension of the spring 7 adjusted by the set screw 9. The piston 6 rises quickly and traverses the passage 26 until the latter is in communication with the chamber 3 below the piston when the pressure will cause the fluid to pass through the conduit 26 and by the valve 25 into the chamber 21 and so into the Bourdon tube 27 causing the latter to straighten. Normally the bridging piece 30 is in electrical contact with the fingers 35 and the electric circuit of which the fingers 35 form the terminals is completed at this point. As soon as the Bourdon tube is straightened by the pressure transmitted thereto the bridging piece 30 is moved out of contact with the fingers 35 and ultimately makes contact with the fingers 34 thus completing the circuit of which the fingers 34 are the terminals, at said fingers.

So long as the pressure is maintained in the pipe 5 the contact is continued at fingers 34, but as soon as the pressure is relieved at the pipe 5 the spring 7 will cause the piston 6 to move toward the end of the chamber 3 containing the valve 12 and the latter will at once close. But because of the leak passage 13 the liquid which has been forced into the chamber 3 against the piston will slowly return to the chamber 2. This liquid cannot pass through the conduit 16 to the Bourdon tube 27 cause of the valve 19, but the latter will open to superior pressure on the Bourdon tube side 115 when the piston 6 has come to rest, permitting the fluid to flow back through 16, so that the pressure within the Bourdon tube may reduce as fast as the liquid may pass through the leak passage 13. On the reduction of pressure in the Bourdon tube its natural tendency to move toward the fingers 35 is exerted and the circuit at the fingers 34 is broken and the circuit at the fingers 35 is ultimately again completed. By this means the circuit may be quickly broken at the fingers 35 after the establishment of pressure in the chamber 2 and the circuit at the fingers 34 may be rapidly completed, but a considerable time will elapse 130

after the pressure in the pipe 5 has been reduced before the Bourdon tube will respond and return to its normal position.

It is sometimes desirable that the initial operation of the Bourdon tube should be slow and its return motion rapid. Under these circumstances the valve 12 may be removed to a seat 36 at the end of the passage or conduit 11 opening into the chamber 12, a suitable cage at 14 being used to prevent the unseating of the valve by the returning fluid and permitting the valve to again assume its normal position. Under these circumstances the flow of liquid from the chamber 2 into the chamber 3 is controlled by the small passage 13 and consequently is slow so that considerable time elapses before the pressure in the Bourdon tube is sufficient to cause the movement of the same to carry the bridging contact 30 into engagement with the fingers 34, but the return movement of the Bourdon tube on the reduction of pressure within the chamber 2 is rapid because the valve 12 will then readily yield to pressure and provide a large return passage for the fluid into the chamber 2.

What is claimed is:

1. An electric switch comprising a pressure responsive circuit controller movable freely in one direction, and means for retarding and regulating the speed of the movement of said circuit controller in the other direction, said means being adjustable at will to determine the direction of retarded movement.

2. An electric switch comprising a circuit maker, a Bourdon tube for operating the same, and a controller for admitting pressure fluid to said Bourdon tube and for permitting the subsequent escape of fluid under pressure, said Bourdon tube acting freely in one direction and sluggishly in the other direction.

3. In combination, a pressure-responsive circuit controller, means for supplying fluid under pressure thereto, and means governing flow of the fluid under pressure to and from the circuit controller to cause a relatively rapid movement of the circuit controller in one direction and a sluggish movement of the controller in the other direction.

4. In combination, a pressure-responsive circuit controller, means for supplying fluid under pressure thereto, and means governing flow of the fluid under pressure to and from the circuit controller arranged to admit the fluid under pressure freely in one direction and to retard its movement in the other direction, whereby to cause a relatively rapid movement of the circuit controller in one direction and a sluggish movement of the circuit controller in the opposite direction.

5. In combination, a pressure-responsive

circuit controller, means for supplying fluid under pressure thereto, and means governing flow of fluid under pressure to and from the circuit controller to cause a relatively rapid movement of the circuit controller in one direction and a relatively sluggish movement in the opposite direction, adjustable to reverse the direction of such movements.

6. In combination, a pressure-responsive circuit controller, a conduit for the supply of fluid under pressure thereto, a supply passage extending from the conduit to the controller, means in said passage for checking a reverse flow back through the passage to the conduit, a return passage extending from the controller back to the supply conduit, means in said return passage arranged to permit a return flow from the controller back to the conduit and to prevent direct flow from the supply conduit through such return passage to the controller, and governing means in the supply conduit adapted to permit free flow of the fluid under pressure in one direction and to retard flow of the fluid in the opposite direction.

7. In combination, a pressure-responsive circuit controller, a conduit for the supply of fluid under pressure thereto provided with valve seats in the opposite ends thereof, and an interchangeable leak valve permitting free flow of fluid in one direction and a retarded flow in the other direction arranged for engagement with the valve seat at either end of the supply conduit.

8. In combination, a pressure-responsive circuit controller, a supply passage leading thereto, a piston chamber into which the supply passage opens, a piston in said chamber controlling the flow through the supply passage, a pressure chamber, a supply conduit extending from the pressure chamber to a point beneath the piston in the piston chamber, valve seats in the opposite ends of the supply conduit within the pressure chamber and piston chamber respectively, and an interchangeable leak valve permitting free flow of fluid in one direction and retarded flow in the other direction adapted for cooperation with either of the said valve seats.

9. In combination, a pressure-responsive circuit controller, a supply passage leading thereto, a valve for checking reverse flow through said passage, a piston chamber into which the supply passage opens, a piston in said chamber controlling entrance to the supply passage, a pressure chamber, a supply conduit extending from the pressure chamber to a point beneath the piston in the piston chamber, a leak valve in said supply conduit adapted to permit free flow of fluid in one direction and retarded flow of fluid in the opposite direction, a return passage extending from the circuit controller back

to the point of entry of the supply conduit into the piston chamber, and a valve in the return passage adapted to permit flow from the circuit controller back to the supply conduit and to check flow from the supply conduit through the return passage to the circuit controller.

In testimony that I claim the foregoing as my own, I have hereto affixed my signature in the presence of two witnesses.
